ROLF SAHLBERG, OF NEW YORK, N. Y., ASSIGNOR TO THE AEROCRETE CORPORATION OF AMERICA, OF NEW YORK, N. Y., A CORPORATION OF DELAWARE

SUPPORTING CONCRETE BEAM

Application filed August 25, 1927. Serial No. 215,375.

This invention relates to the supporting of beams, particularly beams used in concrete building construction, and the object of the invention is the provision of an improved method and improved means for supporting beams upon girders. The invention is directed particularly to the supporting of concrete beams upon steel girders.

In constructing buildings in which the weight of the building is carried upon a structural steel skeleton or framework, and where-in the floors and partitions are of fireproof material, such for example, as concrete, the differences in shape of the steel members of the building, and the concrete members of the building, as well as the physical differences of these two sets of members, renders it difficult to satisfactorily secure the concrete members to the steel members.

In such building construction it is important that the concrete elements or members shall be fastened to the steel members with a high degree of security so that vibration will not be apt to loosen the fastening, and so they cannot become displaced. It is undesirable to merely rest the beams or floor members directly on the tops of the steel girders because then the entire depth of the girder projects below the bottoms of the beams or floor members, and occupies space in the room below. In large buildings, particularly in the lower floors, the depth of the steel girders is sufficient to occupy an undesirably large amount of space in this way. Another substantial consideration is the fact that it is necessary to protect the steel girders against the danger of being weakened by overheating in the event of fire.

These difficulties are to a large degree overcome by my present invention, and the invention will be better understood by referring to the accompanying drawings, together with the following description. It will be understood, however, that the drawings illustrate only one embodiment of the invention in illustrating the principles of the invention. In these drawings:

Fig. 1 is a plan view of a single girder

with a plurality of floor members supported thereon at one end;

Fig. 2 is a vertical section taken on line 2-2 of Fig. 1, showing a completed support or joint structure poured with cementitious material;

Fig. 3 is a vertical section taken on line 3-3 of Fig. 1 centrally through a pair of fins on the two mold forms or parts; and

Fig. 4 is a plan view of one of these mold parts.

It will be understood that the frame of the building consists of a plurality of primary supporting members or girders which are of steel, and on these primary supporting members, secondary members, such as joists, or beams, may be supported, the floor elements or members being in turn supported on these secondary members. On the other hand, the floor elements or members may be supported directly upon the primary members, namely upon the steel girders. The secondary members mentioned above may be made either of steel or of concrete. My invention may be employed in securing concrete beams to the primary members, or in securing concrete floor elements to the secondary members, or in any place where it is desired to secure a concrete load-supporting building element to a steel beam, joist or girder.

Referring now to the accompanying drawings, I have illustrated the invention in connection with the supporting of a plurality of floor elements 10 on the left hand side of a primary member or girder 11, and a plurality of other floor elements 12 on the right hand side of this girder. The girder 11 is of a construction such that it has ledges 13 and 14 on its left and right hand sides respectively, and inasmuch as this girder is of I-beam section, these ledges are just above the bottom of the girder. I make use of these ledges in the formation of my improved joint structure, and particularly during the making of this joint structure.

In carrying out my invention, I first construct mold parts 15 which, as shown in Fig. 4, are elongated bodies having walls, of appropriate shape to form the walls of a con-

crete mold, about the girder 11, when one or more of these mold parts 15 is placed in its intended position in proximity to the girder. The mold part 15, as shown in the accompanying drawings, has vertical side walls 16, and horizontal bottom walls 17 which are joined together at the corner 18 in L-shaped formation when viewed in cross section as may be seen in Fig. 2. Projecting inwardly from the vertical walls 16, at appropriately spaced points there are provided the fins 19, these fins being preferably formed integrally with both the walls 16 and 17. These fins constitute laterally extending formations or wide lugs on the walls 16 for the purpose of supporting the mold part 15 upon the girder 11, as will presently appear.

The mold parts 15 are made of appropriate fire-proof or fire-resisting material which possesses relatively high compressive and shearing strength, that is, a strength comparable to that of the cementitious material which is later to be poured into the mold parts to complete the beam or floor support. Concrete may advantageously be employed for the material of the mold parts of forms 15, and these parts cast in appropriate molds in which are first positioned the longitudinal reinforcing bars 20 usually of steel, and also the metallic reinforcements 21. Concrete of any kind, that is, either ordinary dense concrete, or light weight concrete, such as porous, expanded or aerated concrete may be used. Reinforcement 21 is provided for each of the fins or lugs 19 and may conveniently be made from a steel bar bent to the shape illustrated in Fig. 3 so that the upper portion 22 thereof extends into the upper part of each lug 19 above the ledge 14, and so that the lower part 23 extends into the lower portion of each fin 19 below the bottom of the I-beam, when such lower portion is provided.

In bending this reinforcement 21 it is also convenient to form a loop which extends outwardly into the wall 16 and to make the lower end 23 of sufficient length to extend downwardly into the wall 17. In this way both the upper and lower parts of the fins or lugs 19, are anchored to the walls 16 and 17. Notches 24 are cut deeply into each of the lugs or fins 19 so as to form shoulders adapted to rest upon the ledges 13 and 14 of the girder 11 and support the mold parts or forms 15 thereon, and it will be understood that the upper portion 22 of reinforcement 21 is located above the notch 24, and the lower portion 23 below this notch.

A sufficient quantity of the mold forms or parts 15 are precast, usually under factory conditions, where the materials and molding operations can be carefully controlled so as to insure maximum strength, and these mold parts are supplied to the building which is under construction.

In constructing my improved joint structure, a pair of mold parts 15 are placed upon the girder 11, one on each side, as shown in Fig. 2, with the shoulders of the lugs 19 resting on the ledges 13 and 14 of the girder. Then a clamp 25 of appropriate construction, and indicated diagrammatically in Fig. 2, is placed upon the pair of mold parts so as to hold them in the position shown in this figure, with the inner vertical surfaces 26 of the lugs or fins 19 in contact with the web of the girder 11. The vertical surfaces of the fins 19 are so formed to correspond to the surfaces of the web 11 that the exterior walls 16 are parallel, and so that the edges 27 of the lower wall 17 meet and form a comparatively tight joint running longitudinally beneath the center of the girder. Notches 24 are so positioned vertically in the lugs 19 that the upper edges 28 of the side walls 16 are below the top of the girder 11. This distance below the top of the girder will depend upon the thickness of the floor elements 10. Preferably these dimensions are arranged so that the bottom of the floor elements 10 are well below the top of the girder 11, and the upper surfaces of the floor elements 10 are above the top of the girder only far enough to permit a fire-resisting coating of cementitious material to be placed on the top of the girder in order to protect it.

It will be understood that pairs of mold parts 15 are placed end to end as just described, throughout the length of the girder 11.

A space 29 is provided throughout the length of the girder through which cementitious material may pass to the spaces 30 between the lugs 19 on each side of the girder 11. In order to expedite the introduction of this cementitious material, the corners of the floor elements 10 and 12 are beveled, as indicated in Fig. 1, so as to provide passageways 31 spaced along each side of the girder. Fig. 2 illustrates the completed support structure after the introduction of the cementitious material indicated by reference numeral 32. This material may consist of various cement and water mixtures, included in which may also be appropriate aggregate material, such as sand, or crushed rock of a relatively fine particle size. Various kinds of light weight or highly porous concrete, such as expanded or aerated concrete may also be used as the cementitious material 32, in which case the aggregates mentioned above might be used, but preferably a porous clay clinker should be used.

The cementitious material 32 passes around underneath the bottom of the girder 11 and completely fills all parts of the spaces 30 between the lugs 19. The material also fills the space between the inner ends of the floor elements 10 and 12 and the space above the top of the girder so as to make a smooth continu-

ous floor across the top of the girder when desired. The floor elements 10 and 12 are supported upon the upper edges of the side walls 16 of the mold parts 15 after the mold parts 5 are assembled upon the girder 11, and before the spaces 30 are filled with the cementitious material 32. The inner ends of the floor elements 10 and 12, however, preferably project inwardly beyond the wall 16 so that when the 10 cementitious material 32 has set, the floor elements are then supported partly by this material 32, and partly by the wall 16. The clamps 25 are removed after the cementitious material 32 has set. In setting, the cementitious material 32 interlocks or unites to a greater or less degree with the walls 16 and 17 of the mold parts 15, as well as with all surfaces of the fins or lugs 19. Hence the mold parts 15 become an integral part of the supporting structure for the floor elements 10 and 20 12, and while they serve merely as temporary supports during the assembling and pouring of the joint structure, they also ultimately become a permanent part of this structure.

25 What I claim as my invention and desire to secure by Letters Patent of the United States is:

1. In a building structure, the combination of a primary supporting member having a 30 ledge extending longitudinally thereof on each side, a pair of preformed secondary members disposed at right angles to said primary member and having their bottoms positioned below the top of the primary supporting member and their ends in spaced relation thereto, a pair of mold parts engaging the lower surfaces of said secondary members and having lugs engaging the shoulders on said primary member, and a filling of cementitious material in the spaces between said primary member and said mold parts and the ends of said secondary members.

2. In a building structure, the combination of a primary supporting member having a 45 ledge extending longitudinally thereof on each side, and a transverse portion extending along the top thereof, a pair of mold parts disposed along each side of said primary member having lugs engaging the shoulders on said member, and a plurality of elongated floor elements disposed at right angles to said primary supporting member, the lower surfaces thereof engaging the upper surfaces of said mold parts, and having undercut ends 50 projecting beneath the transverse portion of the primary supporting member, and the corners of said floor elements being beveled to provide a plurality of spaced apertures for the introduction of cementitious material 55 into the spaces between said primary member and said mold part and the ends of said floor elements.

3. In a building structure, the combination of a primary supporting member having a 65 ledge extending longitudinally thereof on

each side, preformed secondary members disposed at right angles to said primary member and having their bottoms positioned below the top of the primary member and their ends in spaced relation thereto, a mold part engaging the lower surfaces of said preformed secondary members and surrounding the lower portion of the primary supporting member and having lugs engaging the shoulders on said primary supporting member, and a filling of expanded concrete in the spaces between said primary member and said mold part and between the ends of said secondary members.

4. As an article of manufacture, a device 80 for securing beams to girders in building construction comprising a mold part of concrete material having vertical and horizontal walls forming a substantially L-shaped body, spaced fins projecting inwardly from the vertical wall of the mold part and upwardly from the horizontal wall thereof, said fins being provided with aligned recesses forming shoulders for supporting the mold part upon the girder and each of said fins having a continuous metallic reinforcement extending from the fin portion above its recess into the fin portion below said recess.

In testimony whereof I affix my signature.

ROLF SAHLBERG.
